UNITED STATES PATENT OFFICE.

CHARLES COTTON, OF INDIANA, PENNSYLVANIA.

DESIGN FOR A CONFECTIONERY-CONTAINER.

44,360.

Specification for Design.

Patented July 22, 1913.

Application filed May 6, 1913. Serial No. 765,901. Term of patent 7 years.

To all whom it may concern:

Be it known that I, CHARLES COTTON, a citizen of the United States, residing at Indiana, in the county of Indiana and State of Pennsylvania, have invented a new, original, and ornamental Design for Confectionery-Containers, of which the following is a specification, reference being had to the accompanying drawing, forming a part thereof.

The figure is a side elevation of a confectionery container, showing my new design.

I claim:

The ornamental design for a confectionery container, as shown.

CHARLES COTTON.
